UNITED STATES PATENT OFFICE

WILLIAM H. BAHAN, OF GREENVILLE, SOUTH CAROLINA

BEAM SUPPORTING MEANS FOR TEXTILE MACHINERY

Application filed July 11, 1929. Serial No. 377,403.

This invention relates to a beam rest or beam lock for looms and other textile machinery, in which it is desired to have a beam rest or beam lock into which the beam can be quickly placed and quickly removed.

It is a well known fact that in warping machines, slashing machines, and in looms, that a beam support is provided into which the beam is adapted to be placed while the 10 thread is being wound therefrom or thereon, and it is an object of my invention to provide a beam rest or beam lock which is capable of being attached to any of these machines, but is more especially adapted to be attached to a loom into which the beam full 15 of the warp thread is adapted to be placed, and then the threads are led from this beam through the loom, and in the drawings are shown my beam rest or beam lock attached to a loom, but I desire it to be understood 20 that it is capable of being attached to other forms of textile machinery where a beam rest or beam lock is adapted to be used and is required.

An object of my invention is to provide a beam rest or beam lock adapted to support the ends of the beam at the bearing portion thereof, said beam rest or beam lock being so constructed as to permit the beam to be 25 quickly placed in the said support or to be quickly removed therefrom, and when placed in position to be locked in adjusted position while the said beam is being used.

Another object of my invention is to provide a beam rest or beam lock into which a beam for a loom can be quickly placed and secured in position, and from which the beam can be quickly removed when the thread 30 therefrom has been exhausted.

Although I have shown only one end of a loom in the drawings, and this end is the end in which the roll of warp is mounted, it is evident that a similar roll is placed on the other end of the loom onto which the cloth 35 is wound after the filling has been placed

therein by the shuttle. My invention, therefore is applied also to the end of the loom on which the cloth is wound on another beam.

Some of the objects of my invention having been stated other objects will appear as 50 the description proceeds when taken in connection with the accompanying drawings, in which—

Figure 1 is a side elevation of one end of a loom showing my beam rest attached there- 55 to;

Figure 2 is an enlarged view of the beam rest looking from the same position as shown in Figure 1, and showing portions thereof in dotted lines;

Figure 3 is an edge view of Figure 2 looking from the left hand side of Figure 2.

Referring more particularly to the drawings the numeral 10 indicates the frame work of a loom proper, and the numeral 11 indicates the beam which is adapted to be placed into the loom, said beam having the gear 12 thereon, which is adapted to be driven by the pinion 13 which is shown in dotted lines together with the take-up mechanism 14 and 60 the dog 15. These parts are conventional in loom structures, thread 16 passing from the beam over the roller 17 and into the loom.

My beam rest has the portion 18 which is adapted to be secured to the side of a loom 65 at each end thereof by means of a bolt 19 passing through the slot 20, said slot 20 permitting vertical adjustment of the beam rest to take care of various sizes of beams and the gears thereon so as to cause the gear to mesh with the pinion 13. This portion 18 has the bearing portion 21 and the rest portion 22, the portion 22 being adapted to receive the journal of the beam before the same is placed into the bearing portion, and act as a 70 rest for the beam before it is secured in the beam rest or beam lock. This portion 18 has bosses such as indicated by the reference character 23 to cause the portion 18 to be 75 firmly secured to the end portion of the loom 80

45 50 55 60 65 70 75 80 85 90 95

at each side thereof. I have shown only one side of the loom but it is understood that the other side of the loom will be equipped with a similar device made in a reversed direction. 5 The portion 18 has the projecting portion 25 on which is pivotally secured the cam 26 by means of the bolt 27 which has the nut 28 thereon, and the lock washer 29 by means of which the cam 26 can be secured in position 10 to hold the movable portion 31 in position. The member 18 has the projecting portion in which is secured the bolt 33 and the portion 31 has the elongated slot 34 into which the bolt 33 is adapted to fit, thus permitting the 15 portion 31 to be slid to the dotted line position as shown in Figure 2 when it is desired to remove or install the beam from the beam support bearing 21.

The portion 31 has the projection 35 which 20 has the hollowed out portion on the lower side thereof into which the set screw 36 is adapted to fit, said set screw 36 being threadably secured in the projection 37 extending from the portion 18 with the lock nut 39 25 thereon to lock the bolt 36 in adjusted position to accommodate shafts of various sizes.

With the parts in the position shown in Figures 1 and 2 the journal of the beam is 30 held in position, but when it is desired to remove the beam from its adjusted position and from the beam rest the cam member 26 is swung to the dotted line position shown in Figure 2, and the portion 31 is then lifted up 35 and slid to the dotted line position as shown in Figure 2, and the beam can be removed from the beam support and a new beam installed and then the portion 31 can be put back into the position shown in Figures 1 and 2 with the cam 26 dropped down also to the position shown in full lines in Figures 1 and 2.

It is thus seen that I have provided a beam rest or beam lock which is capable of being 45 attached to any type of loom, and in fact any type of textile machinery in which a beam rest or beam lock is desired which has the advantages of enabling the beam to be quickly removed therefrom or to be quickly installed therein.

In the drawings and specification I have set forth a preferred embodiment of my invention, and although specific terms are employed, they are used in a generic and descriptive sense only, and not for purposes of limitation, the scope of the invention being set forth in the appended claims.

I claim:

1. In a loom, beam supporting means comprising a stand adapted to be secured to each side of the loom, means for adjusting the stand with relation to the loom, an approximately semi-circular bearing portion in each of the stands, a slidable member mounted on each stand and having a semi-circular bear-

ing portion in the lower face thereof adapted to register with the bearing portion in the stand, means for adjusting the movable member vertically with relation to the stand, and means for securing the movable member in adjusted position. 70

2. In a beam rest and beam lock for looms and the like, a stand adapted to be secured to each side of the loom, a bearing portion in each stand, a slidable member secured to each stand and having a semi-circular bearing portion adapted to register with the bearing portion in the stand, means for laterally adjusting the slidable portion with relation to the bearing portion in the stand, and means for clamping the slidable portion in position. 75 80

3. In a loom, beam supporting means, said means comprising a stand, said stand being adjustable with relation to the loom, a slid- 85 able member mounted with relation to each stand and having a semi-circular bearing portion adapted to register with the semi-circular bearing portion in the stand, means for adjusting the semi-circular bearing portions apart from each other, said semi-circular bearing portions being adapted to coincide, and means for clamping the slid- 90 able member in position. 95

4. In a beam rest and beam lock for looms and the like, a stand, means for adjusting the stand with relation to the loom, a semi-circular bearing portion in each stand, a mem- 100 ber slidably and adjustably mounted on the stand and having a semi-circular bearing portion adapted to co-operate with the bearing portion in the stand to form a complete bearing, means for adjusting the slidable portion with relation to the stand to vary the size of the bearing portion formed by the two parts, and means for clamping the slid- 105 able portion in adjusted position. 110

5. In a beam rest and beam lock for textile machinery, a stand adapted to be secured to two sides of a loom, means for adjusting said stand vertically with relation to the loom, a semi-circular bearing portion in the upper edge of each of said stands, a member slidably mounted on each of said stands and having a semi-circular bearing portion in the lower side thereof, a pivoted member mounted above each of the slidable members, said pivoted members being adapted to be adjusted in position to hold said slidable members in proper position and said pivoted members being adapted to be swung to another position to allow said slidable members to be raised upwardly and slid laterally with relation to the stand. 115 120

6. In a beam support for textile machinery, a stand adapted to be secured to opposite sides of a piece of machinery, semi-circular bearing portions in the upper faces of each of said stands, a movable member mounted on said stand, a semi-circular bearing por- 125 130

tion on the lower side of said movable member, an elongated slot in each of said movable members, a bolt secured in said stand and penetrating said slot, a pivoted member mounted above said movable member and being adapted to normally engage said movable member to hold said movable member in fixed position, said pivoted member being adapted to be swung to another position to allow said movable member to be raised upwardly and slid laterally with relation to said stand when it is desired to remove the beam from said stand.

In testimony whereof I affix my signature.
